US0D1078677S

(12) **United States Design Patent** (10) **Patent No.:** **US D1,078,677 S**
(45) **Date of Patent:** **** Jun. 10, 2025**

(54) **MOBILE PHONE**

(71) Applicant: **HUAWEI TECHNOLOGIES CO., LTD.**, Guangdong (CN)

(72) Inventors: **Yanxin Wang**, Shanghai (CN); **Guotong Zhou**, Shenzhen (CN); **Bin Yan**, Shenzhen (CN); **Bangshi Yin**, Shenzhen (CN)

(73) Assignee: **HUAWEI TECHNOLOGIES CO., LTD.**, Shenzhen (CN)

(**) Term: **15 Years**

(21) Appl. No.: **29/781,593**

(22) Filed: **Apr. 30, 2021**

(30) **Foreign Application Priority Data**

Nov. 2, 2020 (CN) 202030656644.2

(51) **LOC (15) Cl.** **14-03**

(52) **U.S. Cl.**

USPC ..... **D14/138 AB**

(58) **Field of Classification Search**

USPC ..... D14/138 AB, 138 AD, 138 G, 248, 315, D14/316, 317, 318, 319, 320, 321, 322, D14/323, 324, 325, 326, 327, 331, 339, D14/340, 341, 345, 346, 371, 372, 373, D14/374

CPC G06F 1/1652; G06F 1/1641; G06F 1/1647; G06F 1/1616; H04M 1/0268; H04M 1/0214; H04M 1/022

(57) **CLAIM**

The ornamental design for a mobile phone, as shown and described.

DESCRIPTION

FIG. 1 is a front perspective view of a mobile phone showing our new design;

FIG. 2 is a back perspective view thereof;

FIG. 3 is a front view thereof;

FIG. 4 is a back view thereof;

FIG. 4 is a top view thereof;

FIG. 6 is a bottom view thereof;

FIG. 7 is a right side view thereof;

FIG. 8 is a left side view thereof;

FIG. 9 is a front perspective view thereof in a collapsed status;

FIG. 10 is a back perspective view thereof in the collapsed status;

FIG. 11 is a front view thereof in the collapsed status;

FIG. 12 is a back view thereof in the collapsed status;

FIG. 13 is a top view thereof in the collapsed status;

FIG. 14 is a bottom view thereof in the collapsed status;

FIG. 15 is a right side view thereof in the collapsed status; and,

FIG. 16 is a left side view thereof in the collapsed status.

1 Claim, 16 Drawing Sheets
